ELECTRIC IRON WITH PILOT LIGHT

William W. Coons, New Britain, Conn.

Application June 24, 1942, Serial No. 448,243

4 Claims. (Cl. 219—25)

This invention relates to new and useful improvements in an electric iron with a pilot light.

It is proposed that the pilot light be red and be for the purpose of notifying an operator that the iron is ready to be used. An important advantage resides in the fact that the red pilot light reminds the operator whether or not the switch is on or off and thus shows if current is flowing through the iron. It acts as a watchman on duty and is in reality a signal as well as an indicator. If the switch is on and it fails to light it shows that either the iron is defective or there is something defective with the pilot light itself.

It is proposed that the pilot light be red because this color designates danger, and moreover the color scheme is attractive and decorative and works, and stands out in harmony with the design of the iron, and constitutes a good sales item.

An important feature of the invention resides in so mounting and shielding the pilot light that it will not be injured by the heat from the iron. The invention contemplates various ways of mounting and shielding the pilot light for this purpose. The invention also contemplates numerous additional constructions in the interior of the iron.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of an electric iron with a pilot light in accordance with this invention.

Fig. 2 is a perspective view of the iron base plate of the electric iron.

Fig. 3 is a fragmentary sectional and perspective view of the electric heating unit of the iron.

Fig. 4 is a bottom view of Fig. 3.

Fig. 5 is a bottom view of the top plate shown in Fig. 3.

Fig. 6 is a fragmentary enlarged sectional view of the mechanism which supports and operates the pilot light.

Fig. 7 is a view looking in the direction of the line 7—7 of Fig. 1.

Fig. 8 is a side elevational view of an electric iron with a pilot light constructed according to a modified form of the invention.

The electric iron with the pilot light, in ac-

cordance with this invention, includes an iron base plate 10 having a recessed top portion 11 which is provided with a pair of spaced threaded bosses 12 along its longitudinal center line. An electric heating unit 13 is located on said base plate 10 and includes a top insulation plate 14 and a bottom insulation plate 15. A heating winding 16 is located within a groove 17 formed in the bottom face of the top plate 14. This heating winding starts at a contact prong 18 which projects from the top plate 14 and is continuous to a second contact prong 19, except at a point 20 near the front of the iron. At this point 20 the winding is broken and connects with a pair of contacts 21 (see particularly Figs. 3 and 5). The electric iron is provided with a pilot light 22 which is connected with leads 23 which are connected with the contacts 21. Thus the circuit of the heating winding is completed through the pilot light 22.

The insulation plates 14 and 15 of the heating unit 13 are preferably constructed of glass porcelain or other similar insulating material. This construction permits the contacts 21 to be cast as a unit with the insulation plates with the heating winding 16 in position between the plates. Insulation plates so constructed are sturdy, strong and durable and are not subject to the disintegrating or crumbling effects of continued use or unfavorable weather conditions. High temperatures will not cause these insulation plates to smoke or throw off undesirable or unpleasant odors due to the elimination of chemicals commonly found in the old types of insulation members. These insulation plates 14 and 15 are indestructible because there can be no chemical reaction caused by the high temperatures thus eliminating the possibility of short circuits in the heating element. The top insulation plate 14 may be cast with bridges extending across the grooves 17 to maintain the heating winding 16 in position in the grooves, if desired.

The electric iron is also provided with a housing 24 which is extended over the top of the base plate 10 and covers the heating unit 13. A pair of screws 25 pass through the housing 24 and engage the threaded bosses 12 for connecting these parts together. The pilot light 22 is mounted on the housing 24. A certain means is provided for protecting the pilot light 22 from too much heat from the electric iron.

The pilot light 22 is threadedly mounted in a metallic shell 27 which is fixedly mounted in an insulation member 28 vertically slidably mounted in a boss 29 formed downwards from

the top wall of the housing 24. This insulation member 28 has a bottom flange 30 which works in a recess 31 formed in the boss 29 and serves to limit the top position of the insulation member 28. The insulation member 28 is also formed with an opening 32 extended inwards from its bottom end. A heavy, black Bakelite insulation washer 33 is located in the top of the opening 32.

The insulation washer 33 has a contact 34 which engages the end contact of the lamp 32 when the latter is mounted in the shell 27. The contact 34 is connected with one of the leads 23. The other lead 23 is connected with the shell 27. Thus the electric circuit is completed. An expansion spring 35 is disposed within the opening 36 and normally acts to urge the insulation member 28 into a raised position. This spring 35 is insulated from the leads 23 by insulation tubes 36 and 37 which telescopically engage each other, and which are mounted respectively on the insulation washer 33 and on the top wall of the electric heating unit 13.

A finger 36 engages the flange 30 and also engages a longitudinal slot 37 formed in the outer face of the insulation member 28. This finger 36 is threadedly engaged on a steep angle screw 38 which is rotatively mounted through the boss 29. A head 39 is mounted on the top end of the screw 38 and has a small peg 40 extending downwards and normally engaging in a small opening 41 formed in the top of the housing 24. The screw 38 is slightly slidable in the vertical direction. It has a bottom head 42 which is slightly spaced from a support 43 on the boss 29. A spring 44 acts between the support 43 and the head 42 for normally urging the screw 38 downwards.

In the event that the electric iron is going to be used on high heat it is advisable that the head 39 be pulled upwards to disengage the peg 40 from the opening 41 and then the head 39 should be turned to indirectly cause the finger 36 to move upwards. The groove 39 prevents the insulation member 28 from turning. However, the insulation member 28 will be moved upwards to follow the finger 36 by the expansion action of the spring 35. This raises the pilot light 22, as for example indicated by the dot and dash lines 22' in Fig. 1. A heavy black Bakelite washer 45 is mounted on the top of the insulation member 28 around the pilot light 22 to help protect it from the heat. The washer 45 is black in color while the pilot light is red in color. This combination results in a contrast of color which adds to the appearance of the iron. The electric iron is provided with a handle 46 which is supported by side brackets 47 mounted on the top of the housing 24 and held in position by the screws 25.

The rear of the housing 24 is formed with an upwardly inclined tubular extension 50 into which the conventional connection plug is adapted to be engaged for supplying the necessary current to energize the heating winding 16 through the medium of the contact prongs 18 and 19. The interior of the extension 50 is provided with four upwardly extending leaf springs 51. These leaf springs 51 have their bottom ends securely attached to the walls of the extension 50 and their top ends bulged at 52. When the conventional connection plug (not shown on the drawing) is engaged into the extension 50 the bulged portions 52 of the leaf springs 51 will engage the sides of the plug and frictionally

maintain the plug in position within the extension.

The operation of the device is as follows:

When the iron is being used the pilot light 22 will be illuminated. This indicates to the operator that the current is passing through the iron. It serves to prevent the operator from forgetting this fact and allowing the current to pass through the iron when it is his intention to have it turned off.

In Fig. 7 a modified form of the invention has been disclosed which distinguishes from the prior form in the fact that the handle 46 is mounted in position on the iron with brackets 47'. One of these brackets 47' is hollowed out so that a post 48 may extend into it. The pilot light 22a is mounted on this hollowed out bracket 47', and is electrically connected with leads with the heating winding of the electric heating unit 13' through the hollow post 48. In other respects this form of the invention is identical to the previous form and like parts are indicated by like reference numerals.

The operation is also identical to the prior form. When the current is passing through the electric iron the pilot light 22a will be illuminated. However, in this form of the invention the means for protecting the pilot light 22a from receiving excessive heat comprises the construction whereby it is raised above the top of the housing 24.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An electric iron with pilot light comprising an iron base plate, an electric heating unit on said base plate and having top and bottom insulation plates and a heating winding between said insulation plates and being continuous from a pair of contact prongs except at one point where there is a break, a housing with a handle mounted on said base plate and covering said heating unit, a pilot light mounted on said housing and electrically connected across said break in said heating winding, and means for protecting said pilot light from too much heat from said electric iron, comprising an insulation member mounted on said housing and supporting the pilot light, and means for extending said insulation, including a manually turnable screw, a follower finger on said screw normally engaging said insulation member to hold it lowered, and resilient means urging said insulation member upwards.

2. An electric iron with pilot light comprising an iron base plate, an electric heating unit on said base plate and having top and bottom insulation plates and a heating winding between said insulation plates and being continuous from a pair of contact prongs except at one point where there is a break, a housing with a handle mounted on said base plate and covering said heating unit, a pilot light mounted on said housing and electrically connected across said break in said heating winding, and means for protecting said pilot light from too much heat from said electric iron, comprising an insulation member mounted on said housing and supporting the pilot light, and means for extending said insulation

tion, including a manually turnable screw, a follower finger on said screw normally engaging said insulation member to hold it lowered, and resilient means urging said insulation member upwards, and means for holding said screw against accidentally turning.

3. An electric iron with pilot light comprising an iron base plate, an electric heating unit on said base plate and having top and bottom insulation plates and a heating winding between said insulation plates and being continuous from a pair of contact prongs except at one point where there is a break, a housing with a handle mounted on said base plate and covering said heating unit, a pilot light mounted on said housing and electrically connected across said break in said heating winding, and means for protecting said pilot light from too much heat from said electric iron, comprising an insulation member mounted on said housing and supporting the pilot light, and means for extending said insulation, including a manually turnable screw, a follower finger on said screw normally engaging said insulation member to hold it lowered, and resilient means urging said insulation member upwards, and means for holding said screw against accidentally turning, said screw being slightly vertically slidably supported, said latter means, comprising a head mounted on the upper end of said screw by which it may be turned, a pin mounted on said head and engageable with a complementary opening formed in said iron, and resilient means urging said screw downwards to retain said pin in said opening, so that by manually raising said screw said pin will be disengaged from said opening so said screw may be turned.

4. An electric iron with pilot light comprising an iron base plate, an electric heating unit on said base plate and having top and bottom insulation plates and a heating winding between said insulation plates and being continuous from a pair of contact prongs except at one point where there is a break, a housing with a handle mounted on said base plate and covering said heating unit, a pilot light mounted on said housing and electrically connected across said break in said heating winding, and means for protecting said pilot light from too much heat from said electric iron, comprising an insulation member mounted on said housing and supporting the pilot light, and means for extending said insulation, including a manually turnable screw, a follower finger on said screw normally engaging said insulation member to hold it lowered, and resilient means urging said insulation member upwards, and means for holding said screw against accidentally turning, said screw being slightly vertically slidably supported, said latter means, comprising a head mounted on the upper end of said screw by which it may be turned, a pin mounted on said head and engageable with a complementary opening formed in said iron, and resilient means urging said screw downwards to retain said pin in said opening, so that by manually raising said screw said pin will be disengaged from said opening so said screw may be turned, said follower finger being engaged with a vertical slot formed in said insulation member so that said screw may be raised slightly relative to said insulation member when desired.

WILLIAM W. COONS.
